ELECTRICAL INSULATOR

Howard P. Seelye, Royal Oak, Mich.

Application June 22, 1933, Serial No. 677,113

9 Claims. (Cl. 173—321)

This invention relates to improvements in electrical insulators of the single knob type which form the support for one or more electric wires or cables. Such devices are in wide use where electric wiring is supported from cross arms, brackets, posts or the exterior of buildings. The conductors are mounted on such insulators either at an intermediate point or the end of a stretch of wire. In either event the insulators are intended to withstand the stresses imposed by the tension of the wiring. The wiring may thus be carried around a corner or held by the end of its length from the support. In the latter instance this condition is referred to as "dead ending" and the full tension of the length of the wire is applied to the insulator in a single direction. Insulators of this type must, therefore, be able to withstand the stress imposed by the weight and the tension of a line of wire regardless of the direction in which this stress is applied.

To meet these situations, insulators must be of simple, cheap and rugged construction so that they can be affixed in position by the linemen without the use of special tools or the exertion of undue force. In service the devices must be inherently capable of withstanding the stresses produced.

It is a prime consideration in such insulators that the fastening members such as wood screws, bolts or the like shall be firmly held by the insulating part but at the same time removed as far as possible from the wire-attaching part so that the electrical path of leakage is as great as possible.

The best and most commonly used material for the insulating knobs of this type is porcelain. However, it is not feasible to apply a metallic wood screw or other fastening directly to the porcelain itself during manufacture since if the screw is molded in the plastic porcelain and the latter then fired, the temper of the steel in the screw is drawn, the screw is deformed and the shrinkage during drying of the porcelain results in separation from the screw. Imbedding the screw in the finished porcelain is objectionable as being uncertain since the cement or other fastening substance may disintegrate and it is difficult to design a screw-head which will withstand torsion.

My improved design as here described permits the assembly in a simple and cheap manner of the fastening means in the insulating member so that there can be no possibility of the screw

pulling out of the insulating part during the twisting movement of installation.

Another object of my invention is to so fasten the screw in the porcelain part that the pull is evenly distributed entirely across the base of the latter and insures serviceability up to the limit of the strength of the porcelain of which the insulating part is constructed. 5

A further object of my invention is to provide a fastening between the screw and the insulating part which by reason of its mode of application tends to provide a thoroughly reliable firm engagement between the parts. 10

Other objects of my invention will be found to follow from the specific characteristics of the device as illustrated in the accompanying drawing in which,

Fig. 1 is a side elevation of the insulator;

Fig. 2 is a vertical section on the line 2—2 of

Fig. 1;

Fig. 3 is a vertical elevation on the line 3—3 of 20

Fig. 2; and

Fig. 4 is a bottom view partly in section.

As illustrating the preferred form and the essential features of my invention, I have shown 25 by way of example an insulating block, knob or the like 5. This knob is generally cylindrical in form and has a flat circular base 6. The upper portion 7 of the knob is grooved to provide two or more beads 8 by which the electrical path of 30 leakage is increased and greater facility provided for holding tie-wires.

The upper end of the knob 5 carries a saddle 9 which is also customary for accommodating either the electric wires to be supported or the 35 tie-wires therefor.

A central opening 10 forms a passageway transversely through the upper part 7 of the knob and is adapted to receive the electrical conductor or wire and to permit the latter to be 40 drawn up to the insulator from any direction without meeting sharp edges.

The base 6 of the knob has a recess 11 extending axially upward from the base but not as far as the opening 10. This recess is generally rec- 45 tangular in cross-section; that is the recess is extended or flattened as more clearly illustrated in Figs. 2 and 4.

The central portion of the recess has an enlargement of circular cross-section to form 50 grooves 12 in the side walls for the purposes of guiding and centering the shank of the screw.

This screw has been illustrated as a wood screw 13 although a machine bolt, lag screw or the like can also be used as circumstances may 55

d dictate. The screw 13 is of the type which can be threaded into wood without previously boring a hole. The shank 14 of the screw is generally cylindrical and terminates in a flattened eye 15. 5 This eye 15 conforms closely to the cross-section adopted for the recess 11 in which latter it is positioned as shown in the drawing. The eye extends near the top of the recess but not in contact therewith so that its ultimate position 10 will be determined by the fastening means.

The fastening means consists of a transverse bolt 16. This bolt is in the form of a rod of copper or like material having a flaring head 17 and a hollow opposite end 18 normally of the 15 same diameter of the bolt 16. This bolt serves as a rivet and the end 18 can be swaged or upset to compress the rivet and cause the metal thereof to flow laterally.

A passageway 19 is provided in a lower portion 20 of the insulating knob 5 and is preferably arranged in a direction perpendicular to the axis of the opening 10. The ends 20 of the passageway 19 are counter-sunk or flared as clearly shown in Fig. 3. The passageway 19 is only 25 large enough to permit insertion of the rivet 16 so that the head 17 will rest against one opening 20 and the opposite end 18 can be flared by swaging or upsetting to engage the opposite opening 20.

30 The insulator as above outlined permits the assembly of fastening means to an insulator knob of porcelain or analogous pre-formed material.

In making the insulator the eye 15 of the 35 screw-eye 13 is inserted in the recess 11 with the opening of the eye in registry with the transverse passageway 19.

In the course of this movement the cylindrical shank 14 is guided and centered by the grooves 40 12, 12 so that the screw-eye 13 will extend in a direction perpendicular to the plane of the base 6. The rivet 16 is then passed transversely of the passageway 19 and through the eye of the screw-eye. A simple upsetting or swaging operation serves to compress the rivet 16 so that the end 18 is spread and the rivet prevented 45 from endwise movement. At the same time the metal of the rivet 16 is caused to flow to an extent sufficient to completely fill the passageway 19 and the eye 15. At the same time the shank 14 is held by the grooves 12, 12. It follows that the screw cannot rock out of its position perpendicular to the plane of the base 6 and further that the engagement between the eye 15 50 and the rivet 16 is such as to prevent the screw-eye 13 from becoming loose or from being pulled out of the knob 5.

Even greater strength may be given this fastening by filling the recess 11 and the intersecting parts of the screw-eye 13 and rivet 16 60 by means of a substance which will anchor the parts together and extend the area of contact with the knob 5. One such means is molten lead which can be poured down around the screw and into the various crevices around it and also around the intersecting cross-pin. This provides a form of cushion and evens or distributes the strain. Other forms of cement or anchoring substances are equally effective.

70 The knob so assembled may be attached to any convenient support by manual force. The screw 13 can be started into the wood of the support by a light blow after which the knob forms a convenient handle by which the screw may be

twisted and thus drawn up until the base 6 is in contact with the surface of the support.

The heads 17 and 18 of the rivet are countersunk beneath the surface of the knob 5 and on a line circumferentially spaced from the ends of bore 10 and may if desired be covered with insulating cement or other material so that the path of leakage is further obstructed. The rivet 16 extending diametrically across the knob provides for the distribution of any strain that may 10 be imposed during the twisting of the knob. At the same time the lateral extension of the recess 11 to accommodate the eye 15 permits the latter to have an extended bearing in the knob 5 and thus minimize torsional strain. This cushioning 15 effect is even greater when lead or other cement is poured into the recess around the screw-eye and cross-pin as above described.

While I have illustrated the preferred form of the device for the purpose of example, there are 20 many changes in details and arrangements which are within the scope of the invention defined in the following claims.

What I claim is:—

1. In an insulator, an insulating member having an upper transverse wire-receiving opening, a rectangular recess axially through the base of the member, a lower transverse passageway intersecting the recess, a screw-eye having a flattened eye positioned in the recess and in extended contact with the side walls of the latter, and a member in the passageway passing through the eye of said screw-eye.

2. In an insulator, an insulating member having an upper transverse wire-receiving opening, 35 a rectangular recess axially through the base of the member, a lower transverse passageway intersecting the recess, a screw-eye having a flattened eye positioned in the recess and in extended contact with the side walls of the 40 latter, and a rivet through the passageway and the eye of the screw-eye and upset.

3. In an insulator, an insulating member having an upper transverse wire-receiving opening, a laterally extended recess axially through the 45 base of the member, a lower transverse passageway intersecting the recess, a screw-eye having a flattened eye positioned in the recess and in extended contact with the side walls of the latter, and a member in the passageway, passing 50 through the eye of said screw-eye.

4. In an insulator, an insulating member having an upper transverse wire-receiving opening, an axial recess through the base of the member, 55 guide grooves in said recess, a lower transverse passageway intersecting the recess, a shouldered screw-eye and a member in the passageway and drawing the shoulder of the screw-eye into said guide grooves.

5. In an insulator, an insulating member having an upper transverse wire-receiving opening, an axial recess through the base of the member, a lower transverse passageway intersecting the recess, a screw-eye in the recess and a deformable rivet in the passageway and passing 65 through the eye of said screw-eye.

6. In an insulator, an insulating member having an upper transverse wire-receiving opening, a recess through the base of the member, said recess being oblong in cross-section, a groove extending axially of the member centrally of each long side of said recess, a lower transverse passageway intersecting the recess in the same plane with said grooves, a screw-eye in the recess and a deformable rivet in the passageway 75

- and passing through the eye of said screw-eye.
7. In an insulator, an insulating member having an axial recess through the base thereof, a transverse passageway intersecting the recess, 5 a screw-eye in the recess, a member passing through said screw-eye, and anchoring means in the recess around said screw-eye and member.
8. In an insulator, an insulating member having an upper transverse wire-receiving opening, 10 a laterally extended recess axially through the base of the member, axial guide grooves in said recess, a lower transverse passageway intersecting the recess centrally thereof, a shouldered screw-eye and a member in the passageway

passing centrally through the screw-eye and drawing the sides of the latter into extended torsional contact with the walls of the recess around the said lower transverse passageway.

9. In an insulator, an insulating member having wire holding means, a recess extending axially into the base of the member, said recess having opposed parallel flat sides, an attaching member insertible into said recess and having one end formed with similar opposed flat sides 10 and means for holding the end of the said member in the recess with the sides of the member in extended contact with the sides of the recess.

HOWARD P. SEELYE.
